CLIPBOARD

Jack Fairchild Fleming, Summit, N. J., assignor to Sterling Plastics Co., Union, N. J., a corporation of New Jersey

Application June 13, 1957, Serial No. 46,575

Term of patent 14 years

(Cl. D74—1)

Fig. 1 is a top plan view of a clipboard embodying my new design;

Fig. 2 is a side elevational view looking in the direction of the arrows 2—2 of Fig. 1;

Fig. 3 is a bottom plan view looking in the direction of the arrows 3—3 of Fig. 2; and

Fig. 4 is an end elevational view thereof looking in the direction of the arrows 4—4 of Fig. 2.

I claim:

The ornamental design for a clipboard, substantially as shown.
